UNITED STATES PATENT OFFICE

GEORGES KLEIN, OF PARIS, FRANCE

WINDOW ASSEMBLY

Application filed August 20, 1931, Serial No. 558,268, and in Belgium September 25, 1930.

The present invention relates to window assemblies.

One of the objects of the invention is to provide an assembly including a sliding window capable of being rotated when in closed position to permit cleaning of the exterior surface thereof.

Another object is to provide means for quickly and easily changing the pane in a window of the sliding-rotating type.

An additional object is to provide means for reducing air leakage in assemblies of the type hereinabove referred to.

Still further objects will appear in the course of the detailed description now to be given reference being had to the accompanying drawings in which:

Fig. 1 represents, in elevation, one illustrative embodiment of the invention;

Fig. 2 is a section taken on line 2—2 of Fig. 1;

Fig. 3 is a section taken on line 3—3 of Fig. 1;

Fig. 4 is a section taken on line 4—4 of Fig. 1;

Fig. 5 is a section taken on line 5—5 of Fig. 3;

Fig. 6 is a section taken on line 6—6 of Fig. 3;

Fig. 7 is a section taken on line 7—7 of Fig. 6;

Fig. 8 shows, in elevation, an auxiliary element designed to be mounted on assemblies of the type represented in Figs. 1 to 7.

Referring to the various figures of the drawings, there is shown an assembly composed of the following elements: a fixed casement *a*; a fixed upper abutting section *b*, a pane *c*; pairs of horizontal and vertical edge strips *d* of U-section; a rotatable frame *e* adapted to enclose pane *c*; an abutment *f* positioned to limit the upward movement of pane *c*; a guiding assembly *g* mounted on frame *e* and including pairs of vertical guiding elements *g*¹ and *g*² of the approximate

sections shown in Fig. 2 and held together by screws *h*, said guiding elements having positioned in spaced relation to, and lying out of alignment with, one another, and being formed so as to guide edge strips *d*; a pair of male and female pivoting elements *i*¹, *i*², mounted on elements *b* and *e* respectively; a transverse bar *j* mounted to slide in fixed guides *k* rigidly attached to casement *a*; a male-female pivot *l*¹, *l*², mounted in alignment with *i*¹, *i*² and attached to elements *e* and *j* respectively; a pair of prehensile elements *m* (Figs. 1, 6 and 7) riveted to lower horizontal strip *d* and bent to engage in a recess *n* formed in transverse bar *j*; an adjustable stop *p* (Fig. 7) adapted to contact with a tail *p*¹ formed on bar *j* to regulate the upper limit of movement of bar *j*; a lever *q* attached to a balancing assembly of the type described in the inventor's prior Patent No. 1,639,094, issued 12/28/28 and operable by a rotatable or other element (not shown) to displace bar *j*; a frame *r*, adapted to fit interiorly over the joint between frame *e*, and elements *a*, *b* and *j* to diminish air leakage and provided with holes *t* fitting onto properly positioned supporting pins (not shown) and a pair of vertical exterior strips *s*, one fastened exteriorly to casement *a* and the other to frame *e*, and serving to further diminish air leakage without interfering with the rotation of frame *e*.

The hereinabove described assembly operates in the following way: Assuming the assembly to be in the position shown in Fig. 1, lever *q* may be operated to raise and lower element *j* so as to move pane *c* upward and downward, guides *g*¹, *g*² and *k* acting to guide the movement of the extremities of element *j* and vertical strips *d*; if it be desired to clean the exterior of pane *c*, lever *q* is moved upward until elements *p* and *p*¹ contact, and frame *e* is then rotated about central vertical axis A—B (pivots *i*¹, *i*² and *l*¹, *l*²) so that its exterior surface is turned interiorly, ele-

ments *m* disengaging from openings *n*; after cleaning, pane *c* and frame *e* are again rotated through 180° into normal closed position; if it be desired to then cut off any possible leakage, frame *r* is mounted interiorly so that holes *t* fit in their supporting pins.

Should pane *c* be broken, for any cause, it may be rapidly changed by removing screws *h* (note that they face interiorly), separating 10 guiding elements *g*¹ and *g*², blocking lower horizontal strip *d* temporarily in position in any convenient manner, lowering bar *j* so that lower male and female pivots *l*¹, *l*² disengage, removing assembly *e*, *d*, *c* by disengaging 15 upper pivots *i*¹, *i*², removing strips *d* and re-assembling in reverse order with a new pane in place.

What I claim is:—

1. In combination, a fixed casement, guiding means rigidly attached to said casement, a transverse element slidably mounted, in said guides, a pane, and a rotatable slidably, frame assembly supporting said pane and pivotally supported on said transverse element, said frame assembly including pairs of lateral, exterior and interior guide elements and means maintaining corresponding interior and exterior guide elements in assembled relation on opposite sides of said pane.

2. A structure as defined in claim 1 in combination with edge strips fitting around the edges of said pane.

3. A structure as defined in claim 1 in combination with means operative to balance the 35 combined weight of said pane and rotatable frame assembly.

4. A structure as defined in claim 1 in combination with a detachable frame adapted to fit over the joint extending around said rotatable frame.

5. A structure as defined in claim 1 in combination with a pair of vertical, exterior, weather strips positioned to cover the vertical joint portions of said rotatable frame.

45 6. In combination, a fixed casement, guiding means rigidly attached to said casement, a transverse element slidably guided by said guiding means, means for displacing said transverse element, a pane, a rotatable frame assembly pivotally supported on said transverse element, and prehensile means operative to couple said frame assembly to said transverse element when said frame assembly is in normal closed position.

55 7. In combination, a fixed casement, fixed guiding elements attached to said casement, a transverse element slidably guided by said guiding elements, a pane, a rotatable pane supporting frame assembly pivotally supported on said transverse element and including a pair of exterior and interior pane guiding elements, means for maintaining said last named guiding elements in assembled relation and means for pivotally supporting 60 said rotatable frame on said transverse ele-

ment, and means operative to balance and displace said transverse element.

8. A structure as defined in claim 1 in combination with means for adjusting the course of said transverse element.

9. A structure as defined in claim 1 in combination interposed between said casement and said transverse element for varying the course of the latter.

In testimony whereof I affix my signature.

GEORGES KLEIN.
